Primary Examiner — Brian N. Vinson(74) *Attorney, Agent, or Firm* — Quarles & Brady LLP; James J. Aquilina(57) **CLAIM**

The ornamental design for a lighting device, as shown and described.

DESCRIPTION

FIG. 1 is a front perspective view of a lighting device showing our new design;

FIG. 2 is a front view thereof;

FIG. 3 is a rear view thereof;

FIG. 4 is a left side view thereof;

FIG. 5 is a right side view thereof; and,

FIG. 6 is a top plan view thereof.

The dashed broken lines in the Figures show unclaimed portions of the lighting device. The oblique line shading in FIGS. 1 and 2 shows a translucent or transparent material. The bottom view is omitted and forms no part of the claimed design.

1 Claim, 6 Drawing Sheets(56)
